UNITED STATES PATENT OFFICE.

BALFOUR C. SNYDER, OF BROOKLYN, NEW YORK, ASSIGNOR TO MERGENTHALER LINOTYPE COMPANY, A CORPORATION OF NEW YORK.

TYPOGRAPHICAL MACHINE

1,117,713.

Specification of Letters Patent. Patented Nov. 17, 1914.

Application filed August 26, 1914. Serial No. 853,594.

To all whom it may concern:

Be it known that I, BALFOUR C. SNYDER, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532 to O. Mergenthaler, wherein circulating matrices are released from a magazine in the order in which their characters are to appear in print and then assembled in line together with spacers, the composed line transferred to the face of a mold, the mold 15 filled with molten metal to form a slug or linotype against the matrices which produce the type characters thereon, and the matrices and spacers thereafter returned through distributing mechanism to the magazines from 20 which they started.

More particularly, it relates to the means whereby, after the slug is cast, the matrices and spacers are restored to their places of storage, and it is a principal purpose of my 25 invention to prevent the too sudden and violent action of some of these parts in certain circumstances, as will hereafter more fully appear from the detailed description thereof.

30 In the accompanying drawings, I have shown my invention in preferred form and by way of example, and as applied to a linotype machine, but many changes and variations may be made therein, and in its mode 35 of application, which will still be comprised within its spirit. Generally speaking, I desire it to be understood that I do not limit myself to any specific form or embodiment, except in so far as such limitations are specified in the claims.

Referring to the drawings: Figure 1 is a side skeleton view, partly broken away, of a portion of a linotype machine, having my improvements applied thereto; Fig. 2 is a 40 similar rear view; Fig. 3 is a front view, on an enlarged scale and partly broken away, of the matrix and spacer transfer devices, etc.; Fig. 4 is a somewhat similar view, showing the parts in different position; and 45 Fig. 5 is a sectional detail of the yielding abutment.

As illustrated in the Mergenthaler patent previously referred to, or as is customary in the somewhat modified commercial linotype machine, after the slug is cast, and the first elevator G rises to its uppermost position, the line of matrices X and spacers Y is transferred therefrom by the slide S into the upper transfer channel R, where the matrices engage with the second elevator bar A. The bar A is carried by the arm B provided with an arm C located in suitable position to be engaged and actuated by the cam D, whereby the bar is moved upwardly into registration with the distributor box 70 E, to which the matrices are shifted in the ordinary way. The spacer hook U is operatively connected to the slide S, in such manner that when the slide moves the line into the transfer channel, the hook advances 75 and engages the spacers remaining therein, and by its return movement restores them to the spacer magazine U'. The slide S is held in its retracted or inoperative position by the pivoted pawl or detent F. In normal 80 operation, the detent F is tripped to release the slide by the contact therewith of an abutment connected to the second elevator, in such manner that when the latter descends into operative relation to the channel 85 R, the slide is permitted to operate. The parts so far described are or may be of any usual or preferred construction, and except as hereinafter specified constitute no part 90 of my present invention.

The means for actuating the slide S and hook U are somewhat similar to those presented in Letters Patent of the United States to O. Mergenthaler, No. 557,000, wherein the parts are designated by substantially the same reference characters. The slide S is operated by the intermediate link s^8 connected to an upright arm s' mounted upon a shaft (designated herein by the letter L), which shaft has a depending arm s^{11} arranged to bear against the side face of the cam wheel s^{12} . This shaft is also provided with a second depending arm connected by a link or turn buckle s^4 with the arm s' , which carries the spacer hook U. The shaft, and consequently the arm s^7 and the connected arm s' , are operatively moved by the powerful spring 8 connected to an arm 9 fixed on the shaft. The return movements of the shaft and arms are effected by the action of the cam s^{12} on the arm s^{11} . The cam is so formed that when the spring 8

acts to shift the slide S inwardly, its movement is controlled and uniform, as is necessary to secure the proper transfer of the matrices to the elevator bar A, as a sudden or jerk action would project them violently and spill them into the machine.

It sometimes happens in use that the elevator bar A is prevented from descending at the proper time, as for instance when due to the arrest of the distributor, the matrices accumulate and a jam occurs which holds the elevator bar in its uppermost position. When this happens, it is necessary for the operator to leave his place at the keyboard and pass to the rear of the machine, in order to correct the difficulty and clear the parts. At this time, the slide S is held in its outward or inoperative position against the force of the spring S¹² by the detent F, although the cam S¹² has continued to move and has passed out of contact with the arm S¹¹, as indicated in Fig. 2. When now the second elevator is freed and permitted to descend, that is to say, if it be equipped with the customary form of abutment, it trips the detent F and releases the slide S, which shoots forward with great rapidity, because it is no longer under the control of the cam, and projects the line in front of it with excessive violence and frequently with disastrous results. This difficulty subjects the operator to great inconvenience, and entirely because it has been difficult in actual practice to control the slide simultaneously with the clearing and lowering of the second elevator.

To overcome these objections, I have provided means whereby the elevator fails to release the detent when the transfer device is not under the control of the cam, and specifically I secure this result by substituting a yielding member for the rigid abutment previously mentioned upon the elevator arm. In the form illustrated (Fig. 5), this device comprises the longitudinally movable pin or stud M, the spring M' tending to hold it in normal or advanced condition, and elements such as the nuts M² for regulating the tension of the spring.

In ordinary circumstances, as when the machine is operating in the regular way, the strength of the spring is adequate to trip the detent F and thus unlock the transfer devices, which conditions are shown in Fig. 4. However, if for any reason, such as the failure of the second elevator to descend into operative relation to the upper transfer channel, the transfer mechanism starts to operate without being unlocked, the slide S engages the end of the detent F, and the parts are held against the pull of the spring S, it being observed that the arm S¹¹ is no longer in contact with or controlled by the cam S¹². When subsequently the

second elevator descends and the pin M contacts with the detent, instead of tripping the latter and permitting the unrestrained action of the transfer devices, the spring M' yields against the resistance afforded by the strong engagement of the slide S with the end of the detent, thereby obviating the objections previously noted, this yielding action of the detent being indicated in Fig. 3. In order now to restore the parts to normal working relation, the operator moves the slide S rearwardly to a sufficient extent to release the detent, which is then tripped by the compressed spring M', after which he eases the parts over gradually and gently.

As previously stated, I have shown my invention only in preferred form, and by way of example, and as applied to a linotype machine, but obviously many modifications and alterations therein, and in its mode of adaptation, will suggest themselves to those skilled in the art, without departure from its scope.

Having thus described my invention, its construction and mode of operation, what I claim and desire to secure by Letters Patent of the United States is as follows:

1. In a typographical machine, the combination of a transfer device, locking means therefor, an elevator to release said locking means, a cam to control the movement of the transfer device, and means whereby the elevator will fail to release the locking means when the transfer device is not under the control of the cam.

2. In a typographical machine, the combination of the spring-actuated transfer device, the locking means therefor, the second elevator to release said locking means, the cam to control the movement of the transfer device, and means whereby the elevator will fail to release the locking means when the transfer device is not under the control of the cam.

3. In a typographical machine, the combination of the line transfer device, the latch for locking it normally against action, the second elevator for moving the latch to unlocking position, and a yielding member through which the elevator effects the movement of the latch.

4. In a typographical machine, the combination of the line transfer device S, the latch F for locking it normally against action, the second elevator A; and a yielding member M carried by the elevator to engage the latch.

In testimony whereof, I have affixed my signature in presence of two witnesses.

BALFOUR C. SNYDER.
